UNITED STATES PATENT OFFICE.

FRANK M. HEATH, OF PORTLAND, OREGON.

HEEL-PLATE.

1,004,647

Specification of Letters Patent.

Patented Oct. 3, 1911.

Application filed October 3, 1910. Serial No. 585,076.

To all whom it may concern:

Be it known that I, FRANK M. HEATH, a citizen of the United States, residing at Portland, in the county of Multnomah and 5 State of Oregon, have invented a new and useful Heel-Plate, of which the following is a specification.

It is the object of the present invention to provide a heel plate which will retain the 10 heel of the shoe in shape, the heel plate being so constructed that it is peculiarly adapted for the use of those whose ankles are weak, the bottom of the heel plate being peripherally thickened, to withstand the 15 wear incident to the heel plate striking the ground at an angle to the horizontal.

In the drawings.—Figure 1 shows the invention in perspective; Fig. 2 is a section on the line A—B of Fig. 1; and Fig. 3 is a 20 fragmental section on the line C—D of Fig. 1.

The heel plate forming the subject matter of this application is preferably, although not necessarily fashioned from metal and 25 consists of a bottom 1 and an upstanding peripheral flange 2, adapted to engage the heel of the shoe, the bottom 1 having a shoulder 3, outstanding beyond the outer face of the flange 2 for a portion only of 30 the periphery of the heel plate, the bottom 1 gradually increasing in thickness from a point adjacent its center, toward the periphery of the shoulder only, as shown at 4. If desired, the upper edge of the flange 35 2 may be turned inwardly, as shown at 5, to engage the heel. Upstanding from the

bottom 1, is a pin 6, adapted to enter the heel, and suitable openings 7 may be provided in the bottom 1 whereby the heel plate may be nailed to the heel.

The outstanding shoulder 3 will be found useful in the case of persons whose ankles are weak, and in the case of those whose feet strike the ground at a peculiar angle, in 40 walking. By reason of the thickening of 45 the bottom 1, denoted by the numeral 4, the bottom will be reinforced at places subjected to most severe wear, it being understood that the shoulder 3 may be positioned about the periphery of the heel plate, in such a 50 manner as the exigencies of the case may demand.

Having thus described the invention what is claimed is:—

As an article of manufacture, a heel plate 55 consisting of a bottom and an upstanding peripheral flange to engage the periphery of the heel, the bottom having a shoulder outstanding beyond the outer face of the flange for a portion only of the periphery 60 of the heel plate, the bottom gradually increasing in thickness from a point adjacent its center, to the periphery of the shoulder.

In testimony that I claim the foregoing 65 as my own, I have hereto affixed my signature in the presence of witnesses.

FRANK M. HEATH.
